UNITED STATES PATENT OFFICE.

WILLIAM R. KINNEAR, OF COLUMBUS, OHIO.

DESIGN FOR A CEILING-PANEL.

SPECIFICATION forming part of Design No. 25,924, dated August 11, 1896.

Application filed July 3, 1896. Serial No. 598,045. Term of patent 7 years.

To all whom it may concern:

Be it known that I, WILLIAM R. KINNEAR, a citizen of the United States, residing at Columbus, in the county of Franklin and State of Ohio, have invented and produced a new and original Design for Panels for Ceilings, Walls, &c.; and I do hereby declare the following to be a full, clear, and exact description of the same, reference being had to the accompanying drawing, forming a part thereof.

The panel, as shown in the accompanying drawing, is substantially square in its general contour, and around its edges is a line of spindle-work 1. Located on two adjoining sides is a series of rectangular staple-shaped figures or reeding 2, the figures being arranged parallel to each other and their outer ends being curled inward, while at the corner and between the figures 2 are V-shaped figures 3, also having their inner ends curled inward. Between the staple-shaped and V-shaped figures are bars 4, with knobs opposite their ends, and between the elements 2 and 3 is a series of convolutes 5 and spear-shaped figures 6, the convolutes and spear-shaped figures occurring alternately. In the corner opposite the outer ends of the V-shaped reed-

ing is a triangular figure 7, containing a conventional double scroll 8. The ornamentation thus far described occupies about three-fourths of the surface of the panel. In the corner of the panel diagonally opposite the triangular figure 7 is a double conventional scroll 9, having for its base a rosette 10. Intersecting the rosette 10 is a beaded line 11, of ellipse form, which lies on the diagonal of the panel, and at the extremity of the longer axis of the ellipse is a small conventional double scroll 12. Originating at the base of the scroll 9 are two oppositely-curved beaded lines 13, which intersect the sides of the ellipse 11 and terminate in half rosettes 14 at the edge of the panel.

What I claim, and desire to secure by Letters Patent, is—

The design for a ceiling-panel, substantially as herein shown and described.

In testimony whereof I affix my signature in presence of two witnesses.

WILLIAM R. KINNEAR.
